Inventor
Ephraim Louis Jackson
by Knight Bryn *attorney*

UNITED STATES PATENT OFFICE.

EPHRAIM LOUIS JACKSON, OF LONDON, ENGLAND.

TREATMENT OF SEWAGE IN SANITARY CLOSETS.

Application filed December 7, 1927, Serial No. 238,310, and in Great Britain December 20, 1926.

The present invention is an improvement in that type of apparatus for the treatment of sewage in sanitary closets comprising a tank containing a disinfecting fluid to receive 5 the sewage, bearings supporting spindles upon which are mounted means for breaking up the sewage, and mechanism for oscillating and rotating the spindles for the purpose of breaking up the sewage and mixing the 10 chemical therewith. In such apparatus there is a liability for the person using the closet to become splashed with the disinfecting liquid contained in the tank.

The object of the present invention is to 15 overcome this inconvenience.

According to the present invention a shield is normally located beneath the basin and prevents splashing. Such shield is fixed upon a spindle, which also carries the means 20 for breaking up the sewage. Means are provided for oscillating and rotating the spindles sufficiently to cause the shield and the device for breaking up the sewage to enter the disinfectant and to thereby become cleansed. 25 The apparatus is so designed that the shield is normally in the upper position.

The shield may be in the form of a plate and it may be perforated. The plate may be of any suitable form such as convex on its 30 upper surface.

The means for breaking up the sewage may consist of a toothed bar as in the known type of apparatus.

The shield, in one construction, may be in 35 the form of a cylinder carried by arms fixed upon the rotating spindle, and part of the cylinder may carry teeth for the purpose of breaking up the sewage.

The arms may be in the form of propeller 40 blades, upon one of which is mounted a shield in the form of a plate, and in this modification the shield itself and the ends of the propeller blades will break up the sewage.

The invention is illustrated in the accompanying drawings in which:

Fig. 1 is a transverse section of the apparatus taken on the line A—B of Fig. 2.

Fig. 2 is a longitudinal section taken on the line C—D of Fig. 1.

Fig. 3 is a plan of the apparatus shown in Figs. 1 and 2 but with the operating handle omitted.

Fig. 4 is a longitudinal section taken through the tank and showing a modified con-

struction of apparatus. Certain parts are 55 omitted in this figure, which is somewhat diagrammatic.

Fig. 5 is a transverse section through the tank showing a further modification.

Fig. 6 is a detail view showing a plan of 60 the bar provided with pointed teeth and means for retaining the same in the desired position.

Fig. 7 is a transverse section through the tank showing a modification in the means for 65 operating the apparatus.

Fig. 8 is a transverse section through the tank showing a modified method of mounting the shield and breaking up the sewage.

Figs. 4 to 8 are drawn to a smaller scale 70 than Figs. 1 to 3.

Fig. 9 is an enlarged view of the operating mechanism shown in section in Fig. 7.

Referring more particularly to Figs. 1, 2 and 3, *a* is the tank having two apertures *b*, *b* 75 at the upper part thereof. The dotted line *a'* indicates the upper surface of disinfecting liquid. *c*, *c* are two bearings to receive two short spindles *d*, *d* on which are fixed arms *e*, *e* that carry on their outer ends angle bars *f*, *f* 80 having pointed teeth. *g* is a crank attached to the spindles *d*, *d* which is connected by a connecting rod *h* to a vertically sliding rod carrying at its upper end the handle *i*.

In the construction shown the two bearings *c*, *c* are apertures in bars which are also marked with the letter *c*, and which pass across the tank and are fastened at their ends by means of bolts *j* screwing into the ends *c'* thereof which are bent at right angles to the 90 main portion *c*, *c*.

The crank *g* is a two armed crank, each of its arms being connected to one of the short spindles *d*. The connecting rod *h* is connected at its upper end to the lower end of 95 a sliding rod *k* carrying at its upper end the operating handle *i*. The rod *k* passes through a guiding tube *l* which, in the construction shown, is carried by the upper part of a chamber *m* fixed to the top of the tank *a*. 100 The chamber *m* allows a long connecting rod *h* to be employed, the upper end of this latter entering the chamber *m*. The long connecting rod *h* allows the crank *g* and parts carried thereby to be readily rotated.

One of the arms *e*, *e* is carried upwards beyond the spindle *d*, and is bent into a horizontal position at *n*. To this part *n* is fixed a

shield o which, as shown in the drawings, is perforated and is curved downwards at the front and back thereof.

If desired the outer end of the bar n may be connected by a rod p to the toothed angle bar f .

As shown in the drawings, the apparatus is ready for use with the shield o in the upper position. When the handle i is pulled upwards and then pushed downwards it causes the spindles d, d to rotate, and the shield o then passes beneath the disinfectant in the lower part of the tank, and is washed clean and disinfected.

The weight of the toothed angle bars f, f is sufficient to retain the shield o in its upper position and the parts will generally come to rest in this position after the spindles have been rotated.

As shown in the drawings the two apertures b, b are surrounded with short tubes q formed at their upper ends with a suitable flange to receive any usual basin q^1 part of which is only shown in the drawings, as such basins are well known. It is assumed in the drawings that only one basin is employed, and the other tube q is shown closed by means of a cover plate r . If each tube q carries a basin, both of the arms e are carried upwardly and each carries at its upper end a shield o . A second shield o and parts connected therewith are shown in Fig. 2 in dotted lines.

It will be noticed by referring to Fig. 1 that the lower arms e, e are set at an angle to each other. These arms e, e are thus fixed upon the spindles d, d so that the left hand arm e may balance the weight of the crank g and connecting rod h .

In the modified construction shown in Fig. 4 the bearings c, c are arranged at one end of the tank a and the bar n is extended and carries at one end a shield o and at the other end a toothed angle bar f .

The lower part of the arm e carries a balance weight s to normally retain the shield o and the upper toothed angle bar f in the upper position.

If desired the lower part of the arm e may be extended, as shown in dotted lines, and may carry a second toothed angle bar f . This lower toothed angle bar f shown in dotted lines, will probably weigh sufficient to act as a balance weight, and will retain the shield o and the upper toothed bar f normally in their upper positions ready for use.

In the modification shown in Fig. 5 the shield o and the toothed angle bar f have been replaced by a drum t the upper part of which is perforated and acts in the same manner as the shield o , and the lower part of which is provided with teeth u which act like a toothed bar f to break up the sewage contained within the tank a .

In this construction, should the drum not return to the position shown in Fig. 5, some

other part of the drum will be located beneath the aperture b and will act as a shield. The drum t is shown as being carried by arms v which are equivalent to the arms e shown in Figs. 1, 2 and 3. In this modification the drum t and arms v provide means for connecting and supporting the upper part of the drum acting as a shield and the lower part of the drum carrying the teeth u which forms the device for breaking up the sewage.

If desired, a suitable spring catch may be employed to retain the shield o in its upper position without entirely relying upon the use of a balance weight s as shown in Fig. 4 or the weight of a toothed bar f .

As shown in Figs. 4 and 6 there is fixed to the end of the tank a suitably shaped spring w , the ends of which will give way to allow the bar f to pass when it is being rotated by means of the handle i , but the spring w will retain the bar f in the upper position if it is rotated by means of the handle i until it rests within the two ends of the spring w .

The spring w enables the shield o always to be retained in its top position even should the parts get unbalanced due to sewage adhering thereto.

It will be understood that a similar spring w may act in conjunction with one of the toothed angle bars f as shown at the lower part of Fig. 2. A similar spring w fixed to the end of the tank a would work equally well in conjunction with the vertical rod p as also shown in Fig. 2.

The method of driving the spindles d, d and crank g by means of a connecting rod h and operating rod k , shown in Figs. 1, 2 and 3, enables the shield o to be passed beneath the disinfectant in the tank, but it is difficult to cause the spindles d, d to completely rotate and it sometimes happens that the parts stop with the crank g on a dead centre, when it is difficult to move the spindles and parts connected therewith.

To obviate this difficulty, as shown in Figs. 7 and 9 the crank g may be connected to a rod x which passes through a ball y^1 mounted in a casing y . This ball y^1 allows the rod x to slide therethrough and the ball can oscillate within the casing y . At its upper end the rod x carries a suitable handle i which may merely extend on one side of the rod x and be used as a crank handle. With the parts made in the proportion shown in Fig. 7 the handle i will move approximately in a circular path and will cause the crank g to rotate so long as the handle is being rotated. Should the crank be arrested in alignment with the rod x it can easily be moved by a forward or backward movement of the handle i .

As shown in Fig. 8 the shield o is mounted on the end of an arm which is one blade z of a screw propeller and as these parts are caused to rotate they will break up the sewage.

and will mix it with the disinfectant in the tank *a*. The ends of the blades *z* act as teeth and cut and break up the solid parts of the sewage like the toothed bars *f* and the teeth *u*.

5. What I claim as my invention is:—

1. An improved apparatus for treatment of sewage in sanitary closets having in combination a tank to contain disinfectant and provided with an aperture in the upper part 10 thereof, a shield normally located beneath said aperture, an arm by which the shield is carried, a device for breaking up the sewage, an arm by which the said device is carried, a spindle by which the two arms are carried, and means for oscillating and rotating the said spindle to cause the shield and device for breaking up the sewage to enter the disinfectant.

2. An improved apparatus for treatment 20 of sewage in sanitary closets having in combination a tank to contain disinfectant and provided with an aperture in the upper part thereof, a shield normally located beneath said aperture, an arm by which the shield is carried, a device for breaking up the sewage, an arm by which the said device is carried, a spindle by which the two arms are carried, means for oscillating and rotating the said spindle to cause the shield and device for breaking up the sewage to enter the disinfectant, and a spring catch to retain the shield in its upper position beneath the basin, substantially as set forth.

3. An improved apparatus for treatment 30 of sewage in sanitary closets having in combination a tank to contain disinfectant and provided with an aperture in the upper part thereof, a shield normally located beneath

said aperture, an arm by which said shield is carried, a toothed device for breaking up 40 the sewage, an arm by which the said device is carried, a spindle by which the said arms are carried, and means for oscillating and rotating the said spindle to cause the shield and device for breaking up the sewage to enter the disinfectant, substantially as set forth.

4. An improved apparatus for treatment 45 of sewage in sanitary closets having in combination a tank to contain disinfectant and provided with an aperture in the upper part 50 thereof, a shield normally located beneath said aperture, an arm by which said shield is carried, a device for breaking up the sewage, an arm by which the said device is carried, a spindle by which the two arms are carried, bearings for the said spindle formed 55 in bars passing transversely across the tank, and means for oscillating and rotating the said spindle to cause the shield and device for breaking up the sewage to enter the disinfectant, substantially as set forth.

5. An improved apparatus for treatment 60 of sewage in sanitary closets having in combination a tank to contain disinfectant and provided with an aperture in the upper part 65 thereof, a shield normally located beneath said aperture, a device for breaking up the sewage, means for connecting and supporting said shield and breaking up device, and means for oscillating and rotating the connecting and supporting means to cause the shield and device for breaking up the sewage 70 to enter the disinfectant.

In witness whereof I have hereunto set my hand.

EPHRAIM LOUIS JACKSON.
